DESIGN FOR A CASING HEAD FOR WEIGHING SCALES OR SIMILAR ARTICLE

George D. Barok, Columbus, Ohio

Application April 4, 1947, Serial No. 138,158

Term of patent 14 years

(Cl. D52—10)

To all whom it may concern:

Be it known that I, George D. Barok, a citizen of the United States, residing at Columbus, in the county of Franklin and State of Ohio, have invented a new, original, and ornamental Design for a Casing Head for Weighing Scales or Similar Article, of which the following is a specification, reference being had to the accompanying drawing, forming a part thereof.

Fig. 1 is a perspective view of a casing head for weighing scales or similar article, showing my new design;

Fig. 2 is a side elevational view thereof;

Fig. 3 is a rear elevational view;

Fig. 4 is a top plan view.

I claim:

The ornamental design for a casing head for weighing scales or similar article, substantially as shown.

GEORGE D. BAROK.
